[57] **CLAIM**

The ornamental design for a facsimile machine, substantially as shown and described.

DESCRIPTION

FIG. 1 is a top, front and right side perspective view of a facsimile machine showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and

FIG. 8 is a top front and right side perspective view thereof.

The broken line showing of the trays in FIG. 8 is for illustrative purposes only and forms no part of the claimed design.

*Fig. 1**Fig. 2**Fig. 3**Fig. 4**Fig. 5**Fig. 6**Fig. 7*
